COAL WASHERY

George L. Arms, Columbus, Ohio, assignor to The Jeffrey Manufacturing Company, a corporation of Ohio

Application February 7, 1939, Serial No. 254,990

3 Claims. (Cl. 209—13)

This invention relates to a complete self-contained coal washery.

An object of the invention is to provide a complete self-contained washery unit which can be readily installed and which will efficiently clean coal or other material.

A further object of the invention is to provide a compact and extremely simple though entirely complete coal washing unit.

Other objects of the invention will appear hereinafter, the novel features and combinations being set forth in the appended claims.

In the accompanying drawings:

Figs. 1 and 2 placed end to end comprise a side elevational view of the unit comprising my invention;

Fig. 3 is a plan view of the unit;

Fig. 4 is a front end elevational view of the unit; and

Fig. 5 is a sectional view taken substantially on the line 5—5 of Fig. 1 looking in the direction of the arrows.

Referring to the accompanying drawings it will be seen that I have provided a complete self-contained washery particularly adapted for the cleaning of coal, though its use is not so limited. This washery unit comprises a main frame 10 upon which is mounted a jig 11 which, in the illustration, is a single compartment jig though a multiple compartment jig may be employed if desired. The jig 11 may be of any desired construction and for example, may follow the construction of the jig disclosed in Patent No. 2,132,750 for a Jig, to Ernst F. Muller, dated October 11, 1938, though as above stated, the jig 11 is a single compartment jig while the jig of the patent is a two compartment jig.

Briefly described, the jig 11 comprises a base at 12 which is rigidly attached to and forms a part of the main frame 10. Extending upwardly from the base 12 are angle uprights 13 upon which is supported a tank 14. The tank 14 has a receiving lip or chute 15 adapted to receive the raw coal to be cleaned, and a discharge chute 16 adapted to discharge the clean coal with an appreciable amount of water.

As is disclosed in full detail in the above mentioned patent, within the tank 14 there is a reciprocating diaphragm which is mounted on the top of a piston rod 17 which works in a balancing cylinder 18 supplied with air under pressure to counterbalance at least in part the weight of the liquid on the diaphragm. The mentioned diaphragm is reciprocated to effect a pulsating movement of the water through a screen 23 in

5 tank 14 to effect a stratification of the raw coal with the refuse on the bottom and the clean coal on the top, the latter flowing from tank 14 by way of chute 16 as the cleaned product. This reciprocatory motion is provided by virtue of connecting rod means 19 adjustably mounted on rocking beam 20 which is pivotally attached to a bracket 21 carried by channel means 22 which channel means 22 also support the cylinder 18. The rocking beam 20 is provided with a roller 23 adapted to roll between parallel surfaces of a double acting cam 24 which is rotated by a driving motor 25.

10 The jig 11 is also provided with an automatically operable refuse control mechanism including float operating mechanism 26 which controls refuse ejecting mechanism 27 to maintain the refuse on the screen 28 at a predetermined depth, as disclosed in full detail in the above mentioned patent. The jig 11 also includes a refuse elevator 29 which is operative to remove the refuse discharged by the mechanism 27 into the boot of said elevator 29. Elevator 29 also includes a separate drive means including electric motor 30 and appropriate speed reducing drive mechanism 31.

15 Also mounted on the main frame 10 by angle uprights 32 which form a part of said main frame 10 is a dewatering screen 33 which slopes downwardly in a forward direction and which is provided with a receiving chute 34 adapted to receive the clean coal and water from the discharge chute 16 of the jig 11. The dewatering screen 33 is provided with a perforated bottom plate or screen cloth 35 of relatively fine mesh to the end that the water which is received by the dewatering 20 screen 33 may freely pass through the openings in said plate 35 while substantially all of the coal is discharged over the discharge chute 36 at the lower end of said dewatering screen 33.

25 The dewatering screen 33 is mounted for reciprocation on pairs of forward and rearward arms 37 and 38, respectively, and is reciprocated by an eccentric mechanism 39 driven by an electric motor 40.

30 Positioned below the dewatering screen 33 and between the uprights 32 is a water classifying, settling or sludge tank 41.

35 Adjacent the lefthand end of the sludge tank 41 there is formed a clean water or pump sump 42 which is formed by a transversely extending baffle plate 43. Extending longitudinally forwardly from the baffle plate 43 is a plurality of skimming or decanting flumes or troughs 44, each closed at one end (Fig. 2) and each registering at its other end with the openings 43' in the partition 43. These flumes or troughs 44 having bottoms which

slope downwardly to the openings 43' and each upper edge of each trough presents a relatively long effective horizontal weir over which the water in the tank 41 flows in delivering the clarified water through said openings 43' to the sump 42. The closed ends of the troughs are supported by the cross-piece 44' (Fig. 2) between the walls of the tank 41. This decanting mechanism has a very desirable feature in that the water velocities in the tank 41, due to the flow into flumes or troughs 44, are very low, thus allowing for ready settling in the tank 41 of any fine material which comes through the perforated bottom plate 35 with the water.

This decanted or clarified water is used continuously for the operation of the jig 11 by being recirculated by pump 45 provided with inlet pipe 46 which leads to the bottom of the sump 42 and feed pipe 47 which leads to the tank 14 of the jig 11 and is controlled by hand operated valve 48. It may be stated that the pump 45 is driven by an electric motor 49.

To guide the water and any small particles of coal which may find their way through perforate bottom plate 35 into the tank 41, preferably at a position to the right of the flumes or troughs 44, I provide a stationary hopper 50 which is rigidly attached to the uprights 32 and which is positioned below the entire perforated portion of the bottom plate 35 and delivers the liquid and contained small particles of coal through an opening 51 near the head end of the tank 41, as clearly illustrated in Fig. 2 of the drawings.

The function of the settling tank 41, of course, is to allow the small particles of coal received thereby to settle out while decanting the liquid from said tank 41, as above described, thereby clarifying the water for recirculation through the jig 11. It is, of course, necessary to remove the settled sludge from the tank 41 which is formed by the settling of the small particles of coal or other material and to this end the forward wall 52 of the tank 41 slopes, as is clearly illustrated in Fig. 2 of the drawings.

Within said tank 41 I provide a scraper conveyor 53 which travels over substantially the entire bottom of the tank 41 and conveys the material up the inclined or sloping wall 52, discharging it over a discharge lip 54. Scraper conveyor 53 is provided with an appropriate electric driving motor 55 and speed reducing driving mechanism 56.

It is evident that I have provided a very compact and completely self-contained washery particularly adapted to wash coal and separate the pure coal from the refuse such as pyrite, shale and bony coal. The unitary construction, particularly with the compact arrangement of the principal units makes for a minimum of over-all space and a minimum of complication of the washing unit.

In the operation of the unit raw coal to be treated and cleaned is fed to the jig 11 by way of lip or feed chute 15. The repeated upward and downward movement of the water in the jig 11 is effective to stratify the raw coal with refuse in the bottom stratum and coal in the top stratum. The automatic float operating mechanism 26 continuously determines the depth of the refuse stratum and accordingly controls the refuse ejecting mechanism 27 to maintain this stratum of refuse at a predetermined depth within relatively narrow limits. The cleaned coal or upper stratum, along with flowing water, flows from the jig 11 by way of discharge chute 16 and is re-

ceived by the dewatering screen 33 by way of receiving chute 34. The discharged refuse is carried away to any desired point by the refuse elevator 29.

5 The clean coal and water, upon being received by the dewatering screen 33, which continuously vibrates, is separated with the water passing downwardly through the perforate bottom plate 35 of said screen 33, and the coal substantially 10 free of water is discharged over the discharge chute 36 into any desired receptacle, conveyor, hopper, or merely in a pile. The water in passing through the perforate bottom plate 35 will inevitably carry with it some fine particles of coal 15 which, with the water, are guided by the hopper 50 and discharged near the forward end of the settling or sludge tank 41.

Within said settling or sludge tank 41 the coal particles will settle to the bottom, the skimming or decanting troughs or flumes 44 receiving the clarified water and delivering it to the clean water or pump sump 42. The pump 45 operates to recirculate the cleaned water by delivering it from sump 42 to the tank 14 of the jig 11. The settled sludge in the tank 41 is removed by the conveyor 53 which may be operated either continuously or preferably periodically to scrape the sludge therefrom and discharge it over the discharge lip 54 into any desired receptacle, conveyor or hopper.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. Coal washing apparatus comprising a unitary main frame, a gravity separator fixed to said main frame at one end thereof, a settling tank fixed to the opposite end of said main frame, a dewatering screen supported by the side walls of said settling tank, a chute connecting said separator and screen for delivering the overflow from said separator to said screen, means for delivering the liquid passing through said screen to the end of said settling tank opposite said separator and a conveyor mechanism in said settling tank for collecting and dewatering the settleable solids contained in said liquid, the coal passing over said screen and the solids removed from said settling tank being delivered at the same end of said frame and in juxtaposed position.

2. Coal washing apparatus comprising a unitary main frame, a liquid gravity separator fixed to said main frame at one end thereof, a settling tank fixed to said frame at the opposite end thereof from said separator, a dewatering screen carried by said settling tank in a plane above said tank, means to deliver washed coal and the overflow liquid to said screen, means to deliver the drained liquid into said settling tank at the end thereof opposite said separator, means to deliver the clarified effluent from said settling tank into a clear well adjacent said separator and means to collect and dewater the solids settled from said liquid in said settling tank and deliver them at a point juxtaposed to the end of said screen.

3. Coal washing apparatus comprising a unitary main frame, a jig fixed to said main frame

at one end thereof, a settling tank fixed to said main frame at the other end of said main frame, a dewatering screen positioned above said settling tank and supported thereby, means on said jig to pass the overflow including the cleaned coal onto said screen, means carried by said frame to vibrate said screen, means below said screen and above said settling tank to collect the liquid passing said screen and deliver it to

one end of said tank, means in said tank to collect and dewater the settleable solids contained in said liquid and deliver them to a position juxtaposed to the coal delivery end of said screen and means carried by said main frame to recirculate the clarified liquid from said settling tank.
